UNITED STATES PATENT OFFICE.

GEORGE W. LOCKWOOD, OF NUTLEY, NEW JERSEY.

SKIRT-EXTENDER.

SPECIFICATION forming part of Letters Patent No. 514,861, dated February 13, 1894.

Application filed March 27, 1893. Serial No. 467,680. (No model.)

To all whom it may concern:

Be it known that I, GEORGE W. LOCKWOOD, a citizen of the United States, residing at Nutley, in the county of Essex and State of New Jersey, have invented a certain new and useful Improvement in Skirt-Extenders, of which the following is a specification.

My improved extender holds out the lower portion of a skirt to the proper extent by the aid of a flat wire, analogous to hoop-skirt wire, of small size and great length, making a number of circuits in one continuous piece. The wire is inclosed between two thin fabrics, the innermost of which may be smoothly extended and the outermost formed in pockets by lines of stitching, the outer fabric having a little more depth than the inner to allow for the curtailment of length thus caused. I will describe the manufacture as commenced at the bottom. The wire makes a number of parallel circuits extending horizontally around, then diverges and extends upward at a gentle incline three fingers' length more or less, and then extends again horizontally around, but a less number of times; then at another point in the circuit the wire extends again at an inclination upward to a proper height and there again performs two or other number of circuits. It finally ends by making a single circuit, or leaving the upper circuit incomplete. Both ends of the wire proper should be shod with a brass cap, or otherwise shielded to induce a condition to withstand wear at that point and to guard against the tendency to work through the fabric.

Tapes or ordinary flexible strips extend upward from the top of my double fabric to a waist-band, and should be rightly proportioned to support the extender at the proper height. The lower edge may be finished with lace, embroidery or the like.

The accompanying drawings form a part of this specification and represent what I consider the best means of carrying out the invention.

Figure 1 is a perspective view, side. Fig. 2 is a perspective view, front. Fig. 3 is a central vertical section through a portion on a larger scale. Fig. 4 is a corresponding section of a portion on a still larger scale. Fig.

5 is a perspective view of a portion of one of the springs.

Similar letters of reference indicate corresponding parts in all the figures where they appear.

A is the inner fabric and B the outer fabric.

C is a hoop of flat wire. This may be tempered steel, ordinary hoop-skirt wire, extended once around and united by a clasp C'. It performs the ordinary functions of an elastic hoop.

D is a corresponding flat steel wire of less width and thickness, but of a sufficient length to extend many times around the garment. Certain portions will be designated, when necessary, by super-numerals, as D'. This wire is stitched in place, making complete circuits.

Having made four level circuits parallel and close together to constitute a bottom hoop of sufficient rigidity, a continuation D' of the flat wire is inclined obliquely upward in the space between the two fabrics until it attains a proper distance above the lower hoop; there it again makes four level circuits D² close together; then its continuation D³ inclines upward again obliquely to a sufficient height and again makes three complete level circuits; then it inclines upward again, and so on, taking care to arrange the inclined traverses at each level at a different part of the circuit from that of the inclined traverses below. This distributes the effect of these elements so that the action may be practically uniform on all sides. There may be a final upper hoop of one circuit, but I prefer to make the whole of the upper portion a spiral, as indicated by D*. Each end of this long, slender and highly elastic flat steel wire is equipped with a rounded cap E of brass, as has been long practiced with flat wire stiffeners.

The single circuit of the wire C and the several circuits of the slender wire D, D², D³, &c., which constitute the hoops proper, are held in place by a line of stitching G, connecting the fabrics A and B under and over the several coils, which line of stitches may be put in rapidly and continuously by a sewing-machine simultaneously with the introduction of the wire. The stitching should be arranged, as shown, so that it will not only lie

on each side of each circuit of the wire in the several hoops, but also extend along an inclined line on the under side of the portions D', D³, &c., which bridge across the intervals.

5 The lower edge of my skirt extender is finished with a suitable breadth of lace H. The upper edge is hemmed and connected by sufficiently strong and flexible tapes I to a waistband J, which latter is provided with a jam-
10 buckle or corresponding fastener K and per-
forms its usual functions.

The invention is intended more especially for use with the better class of dresses, and for such use the fabric A may be sateen or
15 other tasty material. Silk or satin may serve. It presents a seemly appearance whenever ex-
posed in any exigencies of use.

My stiffener attains the effect of holding the skirt properly distended while presenting
20 the appearance of a corded or analogous flexi-
ble skirt.

Modifications may be made without departing from the principle or sacrificing the ad-
vantages of the invention. The number of
25 circuits of my slender wire in the several ag-

gregations of complete circuits, which I have termed "hoops," may be greater or less than I have specified. There may be a uniform number in all the several hoops. The stouter wire at the extreme bottom may be omitted. 30

I claim as my invention—

In a skirt extender, a series of parallel hoops D, D², D⁴, each formed of several coils with oblique connecting wires D', D³, all in a continuous length inclosed between two fabrics 35 A, B, one within the other, the outermost, A, having an excess of length formed in exterior ridges resembling those in a corded skirt, and having the line of stitches G connecting the two fabrics together and supporting the several coils of the wire, all substantially as herein specified.

In testimony that I claim the invention above set forth I affix my signature in presence of two witnesses.

GEORGE W. LOCKWOOD.
